LETTER OPENER OR THE LIKE

Frederick J. Melges, Battle Creek, Mich., assignor to Walmann Products, Battle Creek, Mich., a firm

Application January 19, 1955, Serial No. 34,083

Term of patent 14 years

(Cl. D74—1)

The dominant features of my design are shown in solid lines.

1 claim:

The ornamental design for a letter opener or the like, substantially as shown and described.
